UNITED STATES PATENT OFFICE

CARL A. HARTUNG AND ERICH WALTER, OF BERLIN, GERMANY

GOVERNOR PROVIDED WITH AN AUXILIARY FORCE

Application filed August 29, 1929, Serial No. 389,293, and in Germany May 14, 1928.

It has before been known to control governors in such a manner that the impulse issuing from any suitable device is increased by an auxiliary force. In all of these known methods and devices the impulse for the regulation must issue from a sender which not only requires some power for its adjustment but which also consumes power for the control of the auxiliary force, that is to say, for intensifying the initial impulse. Thus the forces, sometimes very weak, which are available for conducting the controlling process are additionally strained and in this respect even electric adjusting and controlling devices form no exception.

The new process described hereinafter works without the power consuming governor of the servo-motor coming into action. The device in connection with which the control is carried out can be started by the release of the governing process described below without causing any additional strain. It is perfectly free to move and is affected only by the resistances which are common to the instrument in question. Thus in the case of a galvanometer the hand can swing out without any friction caused by making a contact and in the case of a gas or steam meter, the meter itself follows the slightest measuring pressure and can be moved by the sender without any additional strain (frictional resistances).

This result is obtained by the adjustment of the instrument effecting the impulse at regular shorter or longer intervals and after a previous automatic brief locking of the measuring tool being tested, by means of one or several automatically moved feelers, whereupon by means of these feelers the actual governing element with the auxiliary force applied is adjusted accordingly. Thereupon the controlling element is held in its position until the next and new adjustment by the feelers takes place. Thus the control is effected periodically. The intervals between the controls may however be made extremely short so that it suffices for most practical conditions and in effect corresponds to a continual control. The new construction may however be used with

special advantage for impulse-senders which themselves work periodically, for instance automatic gas testing apparatus. In such a case by altering the apparatus accordingly it is only necessary to be certain that, each time, the termination of the analysis coincides with the producing of the impulse.

In the accompanying drawing one mode of carrying out the invention is illustrated.

The disc *a*, supported by the points of its spindle and subjected to no further friction than that due to this support, is controlled or moved by any kind of a measuring instrument, for instance by a pressure gauge, steam-, gas-meter or the like. The disc *a* carries a pin *b*. At the side of the disc *a* the disc *c* is mounted, the spindle of which is in line with that of the disc *a*. The disc *c* is provided on both sides with the abutments *d* and *e*. The disc is given a turning moment by means of weights *f* suspended from the ends of a thread placed around the circumference of the disc. On the other hand the pin *g* mounted on the side of the disc *c* engages with a rod *h* which is moved—as may be easily understood—by the cam disc *i* on the shaft *k* when the latter is rotating. At the side of the disc *c* a third disc *l* is placed, the axis of which is in line with the axes of the other two discs. Also the disc *l* is provided with an abutment *m* and is connected to a registering device which imparts to it a certain turning moment. Above the disc *a* a brake *o* and above the disc *l* a similar brake *p* are arranged controlled by the cam discs *q* and *r*. Both cam discs are mounted on the same shaft *k* as the cam *i*.

The mode of operation of this apparatus is as follows:

The disc *a* is moved by any suitable device, for instance by means of a pressure gauge as illustrated upon the drawing. The recording should follow the changing indications. The recording device may be replaced by a sender or by the controlling element of any regulator. The shaft *k* is uniformly rotated by clock work or by a motor. The cam disc *q* will then from time to time release the brake *o*, whereby the disc *a* will

be held in its position for a short moment. Then the cam disc *i* against which the rod *h* contacts, releases the disc *c* and the latter is pulled around by the weight *f* until the 5 abutment *d* comes into contact with the pin *b*. In this position the disc *c* is held stationary. The weight *f* must naturally be sufficiently great for holding the disc in its position even at a later stage when it is 10 acted upon by the impulses of the controlling processes. The weight *f* may however be replaced by a spring or another kind of force. Now the cam disc *r* lifts the brake *p* off the disc *l* and the latter is pulled around 15 by the weight of the recording device until the pin *m* rests upon the detent *e*. If the disc *c*, while the cam disc *i* permits free movement of the disc, cannot turn sufficiently far for *d* to come into contact with *b*, as 20 *e* has already previously struck against *m*, the weight *f* will then pull simultaneously the discs *c* and *l* into their correct positions, until *d* strikes *b* after the brake *p* has been lifted.

25 Upon a further rotation of the shaft *k*, in the first instance the brake *p* is again placed upon *l* and the latter is held in this position. By the cam disc *i* the roller on *c* is forced into a lower position with the aid of 30 the rod *h*, that is to say *d* is removed from *b* and at the same time the weight *f* is raised. Finally the cam disc *q* lifts again the brake *o* and the disc *a* can freely adjust 35 itself. In this manner the cycle of operations repeats itself.

It goes without saying that the disc *c* can be replaced by two discs which move in opposite directions. The disc *c* may also be replaced by a suitably mounted feeler and 40 both discs made alike. The principle of the method is not affected at all by such a change. It will also be evident that the movements of the shaft *k* can be caused to take place independently of the measuring 45 instrument controlling the impulses or that the primary measuring apparatus may be so coupled with the shaft *k* that the holding of the disc *a* by the cam disc *q* always occurs at the right moment.

50 We claim as our invention:—

1. In a recorder, a member which is moved in response to variations in the influence to be recorded, means for periodically arresting the movement of said member, mechanical feelers, means to move said feelers to engage said member when in arrested condition, and means for recording the position of said feelers at the time of engagement with said member, said feelers being operated by 55 an auxiliary source of power.

2. In a recorder, a member movable in response to variations in the influence to be recorded, means for periodically braking said member, mechanical feeling means, said feeling means being capable of being moved by 60 65

potential energy to engage said member, recording mechanism operated by said feeler means, means for periodically braking said recording means, and means for controlling both said braking means simultaneously to 70 operate said first braking means and to release said second braking means.

3. In a recorder, a member movable in response to variations in the influence to be recorded, means for periodically braking said member, mechanical feeling means, said feeling means being capable of being moved by potential energy to engage said member, recording mechanism operated by said feeler means, means for periodically braking said 75 recording means, means for controlling both said braking means simultaneously to operate said first braking means and to release said second braking means, and means operable by an auxiliary source of power for 80 storing up the potential energy and to return said feeling means to inoperative position.

In testimony whereof we have affixed our 85 signatures.

CARL A. HARTUNG.
ERICH WALTER.
